ASH TRAY

Cecil B. Woofter, St. Paul, Minn., assignor to
Brown & Bigelow, St. Paul, Minn.

Application August 3, 1953, Serial No. 26,241

Term of patent 14 years

(Cl. D85—2)

To all whom it may concern:

Be it known that I, Cecil B. Woofter, a citizen of the United States, residing in St. Paul, county of Ramsey, and State of Minnesota, have invented a new, original, and ornamental Design for an Ash Tray, for which the following is a specification, reference being had to the accompanying drawings, forming part thereof.

Figure 1 is a top plan view of an ash tray, showing my new design.

Figure 2 is a side view of my design.

Figure 3 is a rear end view thereof.

Portions of the drawing figures are diagonally lined to indicate a shiny opaque surface.

I claim:

The ornamental design for an ash tray, as shown and described.
